UNITED STATES PATENT OFFICE.

BERNIE CHARLES KRIDLER AND JAMES C. BOYLE, OF FLINT, MICHIGAN, ASSIGNEES
TO THE SHINGLE LOCK COMPANY, OF FLINT, MICHIGAN, A CORPORATION OF
MICHIGAN.

METHOD OF CONSTRUCTING SHINGLE ROOFS.

Application filed September 25, 1922. Serial No. 590,262.

To all whom it may concern:

Be it known that we, BERNIE C. KRIDLER and JAMES C. BOYLE, citizens of the United States, and residents of Flint, county of Genesee, State of Michigan, have invented new and useful Improvements in Methods of Constructing Shingle Roofs, of which the following is a full, clear, and exact description.

10 Among the principal objects which the present invention has in view are: to render roofs constructed from shingles weather-tight; to secure regularity in the placement of the shingles of which the roof is constructed; to reduce the time required for the operation of placing the shingles on the roof; to more securely fasten the shingles in service; and to reduce the cost of shingle roofs.

20

Drawings.

Figure 1 is a perspective view showing fragments of roof rafters having the starting or eavesboard for shingle roof covering disposed in place.

25 Figure 2 is a similar view showing the eavesboard as provided with starting shingles and holding clips therefor.

Figure 3 is a similar view showing in addition to what is disclosed in Figure 2, a furring or roofing board secured to the roof rafters.

30 Figure 4 is a similar view showing a series of roofing boards, two of which are equipped with shingle lock clips, the clips being arranged in holding relation to the certain shingles.

Figure 5 is a similar view showing a further amplification of the structure.

40 Figure 6 is a vertical section on enlarged scale showing a fragment of a roof constructed in accordance with the herein disclosed method.

Figure 7 is a cross section of the same, the 45 section being taken as on the line 7—7 in Fig. 6.

Figure 8 is a view similar to Figure 6 showing a section of roof laid in accordance with the modified form of the invention.

Description.

The present invention has for its special object the construction of shingle protected roofs wherein relatively soft or thin shin-

gles are employed together with a protective material such as weatherproof paper or felt is laid or disposed beneath the shingles. When constructing a roof in accordance with the herein disclosed method, an eaves or starting board is permanently secured in position upon and at the terminal ends of roofing rafters 16 as shown in Fig. 1 of the drawings.

The starting board 15 is then covered with a series of short length shingles 17. These are nailed or otherwise firmly and permanently secured on the starting board 15 and over the rear or upper ends thereof are disposed shingle holding clips 18 which have permanently upstanding piercing terminals 19 and resilient clipping or retaining members 20. The retaining members 20 are best seen in Figures 6 and 8 of the drawings.

Having disposed the first series of clips 18 in position the next succeeding furring 75 strip or roofing board 23 is nailed upon the rafters 16 as can be seen best in Fig. 3 of the drawings. In placing the roofing board 23 care is exercised to dispose the same so that the rear or upper edge thereof is removed 80 from the rear or upper edge of the board 15, for a distance equal to the exposed area of the shingles to be held.

As shown in Fig. 4 of the drawings the first tier of long shingles 21 is then placed in position, the rear edge of the roofing board 23 being used as a gage for the placement of the rear ends of the shingles 21. To hold the shingles in this adjustment, the second tier or row of clips 18 is placed in 90 position encompassing the roofing board 23 and the rear ends of the shingles 21. After being thus secured the shingles 21 are forced down upon the upstanding terminals 19 of the first row of clips. If the shingles are 95 such as are not provided with perforations to receive the said upstanding terminals the said terminals are forced through the body of the shingles and then overturned thereupon to thereafter securely hold the shingles 100 in position.

A second roofing board 23 is then nailed to the rafters 16, the rear edge thereof being spaced apart from the rear edge of the first roofing board a distance equal to the exposed area of the shingles. The second tier of long shingles 21 are then placed in position the rear ends of the said shingles coin-

ciding with the rear edge of the roofing board 23 as is best shown in Figures 4 and 5.

Thus it will be seen that conforming with the method herein disclosed the successive roofing boards 23 are spaced apart so that the rear or upper edges thereof are removed each from the other, a distance equal to the exposed areas designed for the shingles to be laid. The shingles are successively laid thereon, each succeeding tier being disposed with the rear or upper ends thereof coincident with the edges of the successive roofing boards, where they are secured by shingle clips 18. Subsequently, the shingles are pressed upon the upstanding terminals 19 of said clips which are then bent back over and upon the shingles which they have pierced or passed through, thereby firmly holding the said shingles while being in turn held by the said shingles in service.

In Figures 6 to 8 inclusive there has been shown an amplification of the method above described embodying the laying of weatherproofing paper or felt 22. Whether the same be as shown in Fig. 6 disposed in one continuous sheet covering the area normally covered by several layers of shingles, or as shown in Fig. 8 where the weatherproofing material 22 is the length of each shingle and disposed between each shingle the method above described is utilized. In both cases it will be understood that the clips 18 are disposed in service position with the terminals 19 overturned when the weatherproofing material is placed in position. In this manner the overturned portion of the exten-

sion 19 is protected from the weather by the weatherproofing strip which is superposed thereon.

Claims:

1. A method of constructing shingle roofs consisting in mounting on the roof rafters shingle supporting members, then mounting thereon shingles, then securing the upper ends of the shingles by forcing resilient clips thereover having upstanding piercing ends, then forcing said shingles upon the piercing ends of previously disposed clips, then bending said piercing ends over said shingles, successive layers of shingles being so disposed as to overlap at their lower ends the bent piercing ends of the clips projected through the underlying shingles. 45

2. A method of constructing shingle roofs consisting in mounting on the roof rafters shingle supporting members with their upper edges spaced apart the length of exposed portions of shingles, then mounting thereon shingles, then securing the upper ends of successive shingle layers by forcing resilient clips thereover having upstanding piercing ends, then forcing the central portions of successive shingle layers upon the piercing ends of the previously disposed clips and bending the ends over the shingle, 55 whereby the lower ends of successive shingle layers will overlap the bent piercing ends of the clips projected through the underlying shingles. 60

BERNIE CHARLES KRIDLER.
JAMES C. BOYLE.
